(57) **CLAIM**

The ornamental design for a mobile phone, as shown.

DESCRIPTION

FIG. 1 is a perspective view of the mobile phone in the unfolded state.

FIG. 2 is a front elevational view of the mobile phone in the unfolded state.

FIG. 3 is a rear elevational view of the mobile phone in the unfolded state.

FIG. 4 is a right side elevational view of the mobile phone in the unfolded state.

FIG. 5 is a left side elevational view of the mobile phone in the unfolded state.

FIG. 6 is a top plan view of the mobile phone in the unfolded state.

FIG. 7 is a bottom plan view of the mobile phone in the unfolded state.

FIG. 8 is a perspective view of the mobile phone in the folded state.

FIG. 9 is a front elevational view of the mobile phone in the folded state.

FIG. 10 is a rear elevational view of the mobile phone in the folded state.

FIG. 11 is a right side elevational view of the mobile phone in the folded state.

FIG. 12 is a left side elevational view of the mobile phone in the folded state.

FIG. 13 is a top plan view of the mobile phone in the folded state; and,

FIG. 14 is a bottom plan view of the mobile phone in the folded state.
